UNITED STATES PATENT OFFICE.

ALBERT NATHEN PORTER, OF PITTSBURG, KANSAS.

SASH-LOCK.

No. 895,193.

Specification of Letters Patent.

Patented Aug. 4, 1908.

Application filed March 12, 1908. Serial No. 420,723.

To all whom it may concern:

Be it known that I, ALBERT NATHEN PORTER, a citizen of the United States, residing at Pittsburg, in the county of Crawford and State of Kansas, have invented certain new and useful Improvements in Sash-Locks; and I do declare the following to be a full, clear, and exact description of the invention, such as will enable others skilled in the art to which it appertains to make and use the same.

This invention relates to an improved sash lock designed for locking both the upper and lower sashes in any desired position.

15 The object of the invention is to provide a device of this class which is simple in construction, cheap to manufacture and efficient in operation, having means for preventing the opening of the device from the outside.

With these and other objects in view, the invention consists of certain novel features of construction, combination and arrangement of parts as will be more fully described 25 and particularly pointed out in the appended claims.

In the accompanying drawings, Figure 1 is a front elevation of a portion of two window sashes showing this improved lock 30 applied; Fig. 2 is a side elevation of a portion of two sashes showing the device in locked position, with parts broken out; Fig. 3 represents a front view of the locking mechanism applied. Fig. 4 shows a perspective view of a slightly modified form of rack bar.

In the embodiment illustrated a base plate 1 is shown having apertures as 2 therein through which the fastening screws as 3 are 40 passed for securing this plate to the top of the meeting rail of the lower sash.

Two perforated spaced lugs 4 and 5 project upwardly preferably from the rear edge of said plate 1 to form bearings for the pin 45 plate 6 of the dog or catch member 7. This member 7 is preferably made as shown provided with a rack engaging terminal 8 having a screw threaded aperture 9 in which is mounted a set screw 10 for a purpose to be 50 described.

The rack bar 11 is secured in any suitable

manner in an upright position to the inner face of one of the side rails of the upper sash as shown in Fig. 1: This rack bar 11 has laterally projecting shoulders 12 with screw 55 threaded apertures 13 arranged beneath each shoulder to receive the set screw 10 of the catch member when it is desired to lock said member securely to the rack bar and thereby prevent disengagement of the catch or dog 7 60 from said rack bar by means of a cane or other implement such as might be used to disengage the dog 7 were this screw not employed.

In Fig. 4 a casting 14 is shown having a 65 single shoulder or tooth 15 with a screw threaded aperture 16 arranged therebelow to receive the set screw 10 of the catch member and it is also provided with the aperture 17 to receive a fastening screw for securing it to 70 the sash rail. When this form is used any desired number may be spaced at a suitable distance along the side rail of the upper sash and secured thereto by screws or otherwise as 75 desired.

In the use of this device the plate 1 having been secured to the upper face of the meeting rail of the lower sash and the rack bar 11 attached to the side rail of the upper sash, the lower sash may be raised and the upper sash 80 lowered the desired distance and the catch 7 engaged with one of the shoulders 12 of the rack bar 11 whereby said sashes are held against movement from the outside.

The set screw 10 is provided when it is desired to more securely lock the sashes against movement.

From the fore-going description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention as defined in the appended claims.

I claim as my invention:—

In a sash lock the combination with a rack 100 bar having laterally projecting shoulders with screw threaded apertures arranged be-

low each shoulder, of a base plate having a pivoted arm or catch provided with a screw threaded aperture at its free end, and a set screw adapted to pass through said aperture and engage one of the apertures in said rack bar.

In testimony whereof I have hereunto set

my hand in presence of two subscribing witnesses.

ALBERT NATHEN PORTER.
